(57) **CLAIM**

The ornamental design for a tractor portion of an articulated work machine, as shown and described.

DESCRIPTION

FIG. 1 is a perspective view showing the front, top and right side of a tractor portion of an articulated work machine having our new design;

FIG. 2 is a right side elevational view thereof, the broken line showing of the trailer is for illustrative purposes only and forms no part of the claimed design;

FIG. 3 is a right side elevational view thereof;

FIG. 4 is a left side elevational view thereof;

FIG. 5 is a top plan view thereof;

FIG. 6 is a front elevational view thereof;

FIG. 7 is a rear elevational view thereof;

FIG. 8 is a perspective view showing the front, top, and right side of a second embodiment of a tractor portion of an articulated work machine having our new design;

FIG. 9 is a right side elevational view of FIG. 8, the broken line showing of the trailer is for illustrative purposes only and forms no part of the claimed design;

FIG. 10 is a right side elevational view of FIG. 8;

FIG. 11 is a left side elevational view of FIG. 8;

FIG. 12 is a top plan view of FIG. 8;

FIG. 13 is a front elevational view of FIG. 8; and,

FIG. 14 is a rear elevational view of FIG. 8.

The bottom surface does not form part of the claimed design and therefore is not disclosed.

The broken line showing is for illustrative purposes only and forms no part of the claimed design.
